R. C. TURNER

ICE CREAM CONE

Filed Nov. 14, 1927

Inventor:

Ralph C. Turner

By George W. Smith
Attorney

UNITED STATES PATENT OFFICE.

RALPH C. TURNER, OF PHILADELPHIA, PENNSYLVANIA, ASSIGNOR TO AMERICAN CONE & PRETZEL COMPANY, OF PHILADELPHIA, PENNSYLVANIA, A CORPORATION OF WEST VIRGINIA.

DESIGN FOR AN ICE-CREAM CONE.

Application filed November 14, 1927. Serial No. 24,121. Term of patent 7 years.

To all whom it may concern:

Be it known that I, RALPH C. TURNER, a citizen of the United States, residing in the city of Philadelphia, county of Philadelphia, and State of Pennsylvania, have invented a new, original, and ornamental Design for an Ice-Cream Cone, of which the following is a specification, reference being had to the accompanying drawing, forming part thereof.

The figure is a perspective of an ice cream cone showing my new design.

I claim:

The ornamental design for an ice cream cone as shown.

In testimony whereof I have hereunto set my name this 1st day of November, 1927.

RALPH C. TURNER.
